UNITED STATES PATENT OFFICE.

PAUL W. FLEISCHER, OF NEW YORK, N. Y., ASSIGNOR TO AMERICAN CAN COMPANY,
A CORPORATION OF NEW JERSEY.

CAN-CLOSING MACHINE.

1,370,804.

Specification of Letters Patent.

Patented Mar. 8, 1921.

Original application filed December 1, 1915, Serial No. 64,494. Divided and this application filed December 6, 1915. Serial No. 65,266.

To all whom it may concern:

Be it known that I, PAUL W. FLEISCHER, a citizen of the United States, residing in New York, in the county of New York and State of New York, have invented a new and useful Improvement in Can-Closing Machines, of which the following is a specification.

The invention relates to can closing machines, and has for its object to enable these machines to be operated successfully by persons who are not skilled, or who are occasionally careless, by automatically preventing the breakage of or injury to those parts of the machine, and their actuating connections, which feed or operate on the can bodies and can ends. It is desired to drive these machines with high power and at comparatively high speed, and in case a can or can end which enters the machine is, through accident or carelessness, not of the size or formation on which the machine has been adjusted to operate, or in case such object is not properly positioned by reason of an unskilful adjustment of some part of the machine, the mechanism may become jammed and the machine stopped against the full power of the prime motor. The result of this is or may be quite serious, requiring the operation of packing to be suspended, with loss of time and material, until a broken or injured part of the mechanism can be replaced or repaired.

According to the present improvement the seaming head or the can end feed, and preferably both of these mechanisms, is or are provided with a yielding or friction driver which overcomes all of the resistance due to the ordinary and designed operations of the machine, but which will yield in the case of unusual obstruction or resistance and allow the said mechanisms to come safely to rest, while the prime motor, and main power shaft or element of the machine driven thereby, may continue to operate until the power is thrown off or cut out. The deformed can body or end can then be removed, the adjustment of the machine perfected if necessary, and the packing (can closing) can be continued without further delay.

With such objects in view, as well as the attainment of all other features of usefulness and advantage which are inherent in the improved can closing machine, the in-

vention consists in the parts and combinations thereof hereinafter set forth and claimed.

In order to make the invention more clearly understood there are shown in the accompanying drawings means for carrying the same into practical effect, without limiting the improvements, in their useful applications, to the particular construction which, for the purpose of example, has been made the subject of illustration. In the said drawings:—

Figure 1 is a rear view of a portion of a can closing machine embodying the invention.

Fig. 2 is a plan view of the upper portion of the same illustrating the driving gearing.

Fig. 3 is a vertical section on line III—III of Fig. 2.

Fig. 4 is a bottom plan view of one of the yielding driving elements.

Fig. 5 is a top plan view of the other of said elements.

Fig. 6 is a vertical sectional view on line VI—VI of Fig. 4.

Fig. 7 is a side view of the lower part of the delivery end of the machine (the right hand end of Fig. 1).

Fig. 8 is a plan view on a larger scale of the right hand part of the table portion of the machine, and attendant mechanism, the upper part and feed end of the machine being removed.

Fig. 9 is a perspective view showing the lever which is tripped by advancing cans so as to cause the can end feed to operate.

Referring to the drawings, from which most of the frame parts have been omitted for clearer illustration, 87 is the seaming head under which the filled and open top cans are fed by a continuously moving chain 52. 84 is a lifter which successively raises the cans through a centering device 252 to receive a can end over its top and be presented to the seaming head. 257 is a slide which delivers the can ends from under a stack holder 254 over the said centering device. 59 is a main vertical cam shaft which drives the feed chain sprocket 50 by a chain 57, the lifter by a cam 103 and a yoke lever 99, and the slide 257 by an eccentric 358. 217' is a vertical shaft which rotates the seaming head and parallel with which the latter is vertically adjustable.

The chain 52 propels the cans by lugs 53, and the cans successively operate the lever 370, which controls the can end feed slide 257, by a rod 367 and other suitable connections, as seen in Fig. 8. The operation of these connections is that if a can body to be closed does not operate the lever 370 the eccentric rod 346 of the eccentric 358 on the shaft 59 will still operate the two-part can 10 end feed lever 326, 329 horizontally, but the lever arm 329 will remain depressed and out of connection with the slide 257 so that a can end will not be fed. The depression of the arm 329 is effected by an angle lever 361 15 swung by the rod 367 and at such time (when the lever 370 is pressed aside by a can) acting to release a vertically movable pin 365 attached to the arm 329. As shown in Fig. 8 a can body has pressed aside the 20 arm 370 and the lever 361 has set free the pin 365 so that the arm 329 is not depressed and may feed a can end:

Normally the arm 329 remains depressed and inoperative being held down by the pin 25 365 and the pin by the lever 361. These features of construction and operation are fully set forth in my companion application now Patent No. 1,330,071 granted Feb. 10, 1920. The can lifter or plunger 84 is shown 30 in Fig. 1. In Fig. 7 it is partly concealed from view by intervening parts. It is supported and raised through the medium of a spring 91 in a housing 90. The lower end of the spring is lifted by a sleeve or slide 89 35 connected by a pair of 'links' 96' with the yoke lever 99.

Located at the top of the frame of the machine is a drive gear casing 377. Extending through this casing and journaled in 40 bearings 378 and 379 is a horizontal power shaft 380. This shaft has keyed thereto and within the casing 377 a worm 381 which meshes with and drives a worm gear 382 mounted near the top of the vertical cam 45 shaft 59. Adjacent the worm 381 and also keyed to the power shaft 380 is a beveled gear 383 which meshes with and drives a bevel pinion 384 fixed on the upper end of the vertical shaft 217' of the seaming head 50 drive gear 217. The gear 217 has preferably formed integral therewith a sleeve 385 which is rotatably mounted in the bracket 138'. The seaming head casing (not shown) and the bracket 138' which is or may be a 55 part thereof are adjustable vertically. In consequence of this the gear wheel 217 and its sleeve 385 are designed to slide vertically on the shaft 217' by means of a feather key 386 (Fig. 1). From this it will be seen that 60 as the casing and bracket 138' are moved the gear 217 will slide vertically on the shaft 217' and always be able to receive power therefrom.

In order that there may be no danger of 65 breakage or damage of any of the numerous

parts operated by the cam shaft 59, because of anything becoming jammed in the mechanism, there is provided at the upper extremity of the vertical drive shaft 59 a yieldable friction driving safety slip or latch device, which will give if anything should arrest the proper operation of the machine. 70

The worm gear 382 is rotatably mounted upon a sleeve 387 keyed to the vertical cam shaft 59. The lower end of this sleeve is 75 provided with an annular collar 388 upon which the worm gear 382 rests. In the upper face of the worm gear is an annular depression 389 in which is secured a case hardened steel latch ring 390. Above the 80 worm gear and vertically slidably mounted upon the sleeve 387 by means of a feather key 391 is an outer sleeve or latch hub 392. This latch hub is also provided at its lower end with an annular surface 393 which bears 85 upon the ring 390 in the worm gear 382. The ring 390 is provided in its upper face with two beveled notches 394 located off center or non-diametrically and adapted to receive and normally retain two case hardened steel beveled latches 395 (Fig. 4) secured in recesses designed to receive the same in the lower face of the collar 393 of the hub 392. Bearing upon the upper face of the collar 393 is a compression latch 90 spring 396 which is adjustably held under tension by a lock nut 397 threaded onto the upper end of the inner sleeve 387. The tension of the spring is made sufficient to hold the blocks in the notches for the transmission of power under ordinary conditions. But if any extraordinary tension is caused by something jammed in the mechanisms driven by the cam shaft 59, the worm gear 95 382 will continue to rotate but will force the 105 beveled blocks 395 up against the pressure of the spring and out of engagement with the notches 394. The blocks 395 will then rest upon the smooth surface of the ring 390 as it rotates until the notches 394 make a 110 complete revolution and again register with the blocks 395, and, if the obstruction is still in the machine, will again force the blocks out of engagement without rotating the 115 drive shaft 59. This will continue until the obstruction or undue tension is removed, and then when the notches and blocks again register they will clutch and rotate as a unit. The tension required to operate the machine 120 under normal conditions is regulated by the nut 397 on the inner sleeve 387, which may be loosened or tightened to lessen or increase the pressure of the spring.

The two beveled blocks 395 and the corresponding notches 394 are located off the 125 diametrical center line. This particular construction is desirable to insure a complete revolution of the worm gear 382 before they can again engage. Were it not for this they would interclutch when they had made but 130

one half of a revolution with increased number of shocks, and might throw the various mechanisms out of time.

By "seaming head" I include various can end attaching means. Such means may be a clencher which crimps the head loosely on to a can, all around the circumference or in spots. Also, when the seaming head is used, only the first operation or curling roll may 5 be put in operation, the complete hermetic seaming by the second operation being done by any suitable means after processing the filled and partly or loosely closed can; and the words "closing machine" are not limited 10 to a machine which hermetically closes the cans.

This application is a division of my co-pending application Serial #64,494, filed Dec. 1, 1915.

20 I do not claim herein the safety coupling device shown in Figs. 4, 5 and 6 excepting in the combinations stated in my claims, said device *per se* being the subject of my application, a division hereof, filed Jan. 26, 25 1921, Serial No. 440,009.

What is claimed is:—

1. In a can closing machine, in combination: a conveyer for feeding filled cans; a seaming mechanism; a centering device below the seaming mechanism; a lifter for delivering the cans to be closed through the centering device to the seaming mechanism; a can end feeding mechanism; a shaft having means for actuating said conveyer, lifter 30 and can end feed; a frictional automatically self yieldable driving latch for actuating said shaft; and a power mechanism for actuating the said driving latch; and a seaming head connected with said power mechanism irrespective of said latch.

2. In a can closing machine, in combination: a conveyer for feeding filled cans; a seaming mechanism; a centering device below the seaming mechanism; a lifter for delivering the cans to be closed through the centering device to the seaming mechanism; a can end feeding mechanism; means whereby the can to be closed controls the can end feed; a vertical cam shaft having means for 45 actuating said conveyer, lifter and can end feed; a frictional and automatically self yieldable driving latch for actuating said cam shaft; and a power mechanism for actuating the said driving latch; and a seaming head connected with said power mechanism irrespective of said latch.

3. In a can closing machine, in combination: a conveyer for feeding filled cans; a seaming mechanism; a centering device below the seaming mechanism; a lifter for delivering the cans to be closed through the centering device to the seaming mechanism; a can end feeding mechanism; means whereby the can to be closed controls the can end feed; a cam shaft having means for actuat-

ing said conveyer, lifter and can end feed; beveled latches and corresponding notches and a spring forming a frictional and automatically self yieldable driving latch for actuating said cam shaft; and a power 70 mechanism for actuating the said driving latch; and a seaming head connected with said power mechanism irrespective of said latch.

4. In a can closing machine, in combination: a conveyer for feeding filled cans; a seaming mechanism; a centering device below the seaming mechanism; a lifter for delivering the cans to be closed through the centering device to the seaming mechanism; a can end feeding mechanism; means whereby the can to be closed controls the can end feed; a vertical cam shaft having means for actuating said conveyer, lifter and can end feed; a worm gear on said cam shaft; a frictional and automatically self yieldable driving latch connecting the worm gear with the cam shaft for actuating said cam shaft; and a power mechanism having a worm for actuating the said worm gear; and a seaming 90 head connected with said power mechanism irrespective of said latch.

5. In a can closing machine, in combination: a conveyer for feeding filled cans; a seaming mechanism; a centering device below the seaming mechanism; a lifter for delivering the cans to be closed through the centering device to the seaming mechanism; a can end feeding mechanism; a shaft having means for actuating said conveyer, lifter 95 and can end feed; a frictional and automatically self yieldable driving latch for actuating said shaft arranged to make a complete revolution before reengagement and maintain the proper timing of the subsidiary mechanism; and a power mechanism for actuating the said driving latch.

6. In a machine for attaching ends to cans, in combination: a conveyer for feeding cans or can bodies; mechanism for operating on the can end to bend the flange of the same; means for holding the can in place relative to the said bending mechanism; a frictional automatically self yieldable connection through which said conveyer is 110 driven definitely timed for automatic reengagement; and power mechanism connected with the said mechanism for operating on the can end and with the said yieldable connection, and actuating the same.

7. In a machine for attaching ends to cans, in combination: a conveyer for feeding cans or can bodies; mechanism for operating on the can end to bend the flange of the same; means for holding the can in place 125 relative to the said bending mechanism, including a can body centering device; a frictional automatically self yieldable connection through which said conveyer is driven; and power mechanism connected with the

said mechanism for operating on the can end and with the said yieldable connection, and actuating the same.

8. In a machine for attaching ends to cans, in combination: a conveyer for feeding cans or can bodies; mechanism for operating on the can end to bend the flange of the same; a can body lifter for holding the can in place relative to the said bending mechanism; a frictional automatically self yieldable connection through which said conveyer is driven; and power mechanism connected with the said mechanism for operating on the can end, and with the said yieldable connection, actuating the same.

9. In a machine for attaching ends to cans, in combination: a conveyer for feeding cans or can bodies; can end feeding mechanism; mechanism for operating on the can end to bend the flange of the same; means for holding the can in place relative to the said bending mechanism; a fric-

tional automatically self yieldable connection through which said conveyer is driven; and power mechanism connected with the 25 said mechanism for operating on the can end and with the said yieldable connection, and actuating the same.

10. In a machine for attaching ends to cans, in combination: a conveyer for feeding cans or can bodies; mechanism for operating on the can end to bend the flange of the same; means for holding the can in place relative to the said bending mechanism; a knockout for ejecting the covered can; a 35 frictional automatically self yieldable connection through which said conveyer is driven; and power mechanism connected with the said mechanism for operating on the can end, and with the said yieldable connection, actuating the same.

In testimony whereof I have affixed my signature hereto.

PAUL W. FLEISCHER.
